(57) **CLAIM**

The ornamental design for a dual cup holder, as shown and described.

DESCRIPTION

FIG. 1 is a top, front, right side perspective view of a dual cup holder showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The evenly dashed broken lines in the drawings illustrate the portions of the design that form no part of the claim. The dot-dash broken lines in the drawings define the bounds of the claim and form no part thereof.
